UNITED STATES PATENT OFFICE.

HENRY F. HELMBOLDT, OF BOSTON, MASSACHUSETTS, ASSIGNOR, BY MESNE ASSIGNMENTS, TO ASAHEL M. SHURTLEFF, OF SAME PLACE.

TOE-CLIP.

SPECIFICATION forming part of Letters Patent No. 597,183, dated January 11, 1898.

Application filed November 25, 1895. Serial No. 569,996. (No model.)

To all whom it may concern:

Be it known that I, HENRY F. HELMBOLDT, of Boston, county of Suffolk, State of Massachusetts, have invented an Improvement in 5 Toe-Clips, of which the following description, in connection with the accompanying drawings, is a specification, like letters and figures on the drawings representing like parts.

My invention relates to toe-clips for use in 10 connection with bicycle-pedals, my invention being especially desirable for use in racing.

My improved toe-clip is so constructed as 15 to embrace the shoe near the toe and so securely hold the same as to prevent the foot leaving the pedal accidentally when running over rough places in a road, at which time the machine is frequently subjected to severe shocks or jars, and also to so cling to the shoe as to enable the rider when pedaling 20 at a very rapid rate to always keep power on the pedal both when in its descending and ascending arcs.

Hitherto toe-clips have extended backwardly over the toe of the shoe and have 25 borne on the top of the foot. The toe-clip of my invention contains a toe-stop against which the toe of the shoe is adapted to rest, the stop being preferably adjustable, and two arms which partially embrace the upper of 30 the shoe and consequently the foot of the rider somewhat back from the toe end of the shoe, said arms permitting free movement of the foot-joints, yet serving to keep the foot down firmly on the body-plate of the toe-clip.

These arms have their portions which rise 35 above the sole of the shoe inclined preferably to conform to the tapering shape of the toe of the shoe, and they are made adjustable to adapt them to the shape of the shoe 40 across the toe.

In the drawings, Figure 1 is a perspective view of one form of my improved toe-clip. Fig. 2 is a bottom plan view thereof. Fig. 2^a shows one of the arms B detached.

Referring to the drawings, the body or foot 45 plate A, preferably of sheet-steel, has a suitable ear a', provided with a slot a² to receive a suitable bolt by which to attach the plate to the bicycle-pedal. At its front end the 50 plate has a toe-stop C, preferably made as an independent piece adjustably secured to the

plate by bolts a³ a⁵, extended through slots c c', nuts N N' being applied to the bolts, part of the toe-stop being guided in a guideway, shown as made by bending two lugs under 55 the plate. By adjusting the toe-stop longitudinally the toe-clip may be adapted to the length of the toe of the shoe.

The arms or grippers B are preferably made by bending two pieces of sheet-steel into the 60 shape shown, one (see Figs. 2 and 2^a) shown as slotted at b to surround the bolt a³ and move thereon between the plate A and one end of the under portion of the toe-stop, certain lips a⁸ being shown as bent under from 65 the plate A to act as guides or holders on the said arms B. A strong spring b⁸, held in place, as shown, by a screw b⁴, acts on pins b² of the arms B and holds them in a yielding manner. There are several of these pins 70 b², and the arms may be slid to the right or left in the guides a⁸ to fit a right or left foot shoe. The toe-stop may be adjusted in the direction of the length of the shoe and the arms in the width of the shoe, each independently of the other, to adapt them to the 75 requirement of the shoe worn by the rider.

The arms or grippers are C-shaped, as shown, to lap over the upper of a shoe at its toe part, the sole of which is pressed on the 80 body-plate, the said arms being adjustable diagonally, as shown, on said body-plate with relation to a line drawn through the latter in the direction of its length, so that the arms are thereby made to adapt themselves to the 85 shape of the shoe toward its ball or widest part.

The arms or grippers B may be of metal more or less resilient.

The arms or grippers engage the shoe or 90 foot between the ball or toe-joints and the toe end thereof to keep the foot correctly and unerringly on the pedals, and the toe-stop keeps the foot from going too far forward; but it will be obvious that the rider has it in his 95 power by quickly retracting the foot to remove the toe of the shoe from the toe-clip, this being necessary in case of threatened accident. The downward curve or spring of the arms over the foot may be more or less, according to the pressure with which it is desired to hold the foot, and to effect this the 100

arms B may be bent more or less. The spring b^3 , acting on the pins b , will normally draw the arms B inwardly to grasp the shoe in a somewhat yielding manner or so that when the shoe is applied between the arms they will be somewhat separated with a spring action. When the arms are to be used in this way, the nut N will be somewhat loosened, so as not to clamp the arms B immovably, and to prevent loss of the nut I have provided the outer end of the bolt with a small cross-pin 16. When the nut N is set down tight, the arms will be held firmly and the spring will not be effective.

Referring to Fig. 2, it will be seen that the width of the arms B is considerably less than the distance between the inner or step edges of the overturned lugs a^8 and that the slots b are wider than the diameter of the bolt a^3 , and as a result of this the arms when the nut N is loosened may be turned more or less to adapt the inner step edges of the arms to the inclination of the edge of the sole of the shoe.

Having described my invention, what I claim as new, and desire to secure by Letters Patent, is—

1. A bicycle toe-clip, composed of a body-plate provided at its rear end with a slotted ear for attachment to the pedal and with guideways, an adjustable toe-stop in the form of a flat slotted strip of metal bent upwardly at its front end above the body-plate, two independent C-shaped slotted arms or grippers, parts of said arms being extended under said body-plate and coöperating with said guideways, the outer free ends of said arms being bent upwardly and inwardly terminating above said body-plate to overlap the upper of a shoe the sole of which is pressed on the body-plate, the said arms being adjustable on

said body-plate to move said outer ends diagonally with relation to a line drawn through the body-plate in the direction of its length, whereby the arms are made to adapt themselves to the taper of the shoe toward its ball, or widest portion, and a suitable bolt to hold the said arms in adjusted position, substantially as described.

2. The body-plate, the adjustable toe-stop, the arms or grippers B, B, and the bolt a^3 and nut N normally loose combined with a device to prevent the escape of the said loose nut, and a spring centrally secured to said plate and connecting at either end to one of said arms or grippers, substantially as described.

3. A bicycle toe-clip, composed of a body-plate provided at its rear end with means for attachment to the forward edge of the pedal, a toe-stop bent up at the front end of and extending above said plate, two independent C-shaped arms or grippers, slotted in their lower ends for lateral adjustment, clamping means to rigidly clamp said arms in desired adjustment on the body-plate to suit different widths of shoes, said arms being located at the rear of said body-plate next to the pedal, and being extended at their upper ends to overhang the body-plate and approximately meeting over the middle rear part thereof to substantially encompass the shoe at its line of flexure in pedaling, forming a pocket into which the shoe of the rider may be inserted at will, substantially as described.

In testimony whereof I have signed my name to this specification in the presence of two subscribing witnesses.

HENRY F. HELMBOLDT.
